PAINT BRUSH

Clayton O. Hange, Wooster, Ohio, assignor to The Wooster Brush Co., Wooster, Ohio, a corporation of Ohio

Filed Sept. 18, 1967, Ser. No. 8,637

Term of patent 14 years

(Cl. D4—38)

FIG. 1 is a perspective view of a paint brush embodying my new design as seen from the bristle end;

FIG. 2 is a top plan view thereof, the bottom plan view being identical;

FIG. 3 is a side elevation view thereof, the opposite side being identical.

FIG. 4 is an end view thereof as seen from the right end of FIG. 3.

The drawing is shaded to show contrast.

The dominant features of my design reside in the portions shown in full lines, the broken line showing of the bristle portions being shown fragmentarily in FIGS. 2 and 3.

I claim:

The ornamental design for a paint brush, substantially as shown and described.
